UNITED STATES PATENT OFFICE

JAMES P. MCKINNEY, JR., OF PITTSBURGH, PENNSYLVANIA, ASSIGNOR TO MCKINNEY MANUFACTURING COMPANY, OF PITTSBURGH, PENNSYLVANIA, A CORPORATION OF PENNSYLVANIA

LATCH MECHANISM

Application filed October 13, 1930. Serial No. 488,208.

This invention relates broadly to latch mechanism, and more particularly to mechanism for reciprocable latches for doors, closets and the like. It relates still more particularly to an improved latch construction which is rendered very easy of assembly and disassembly.

The invention further relates to latch structures of the type having a separately reciprocable bolt member and retractor therefor so that upon pushing closed a door equipped with such a structure the bolt member only is forced back into the casing and the reciprocable retracting member is not operated. Separate springs are preferably provided for the bolt member and retracting member so that although a light tension may be applied to the bolt member alone, as is desirable, a heavier tension may be applied to the retractor, which heavier tension is communicated to the door handle or knob. This is particularly desirable in latch structures of the heavier type in which a firm knob tension should be provided without unduly tensioning the bolt member itself.

I provide latch mechanism comprising a casing, a bolt member reciprocable therein, a retractor for the bolt member reciprocable in the casing, the bolt member and retractor being relatively reciprocable, and separate means within the casing for separately urging the bolt member and retractor outwardly with respect thereto. I further provide latch mechanism comprising a casing, a guide pin mounted on the casing and adapted to extend within the same, and bolt mechanism slidably guided by such pin, such pin being readily detachable from the casing to assist in assembling and disassembling the latch mechanism.

I also provide latch mechanism comprising a casing, a bolt member reciprocably mounted therein, a retractor for the bolt member slidably mounted on the bolt member, means for operating the retractor, and means for deadlocking the retractor while still permitting slidable movement of the bolt member therein.

Other objects and advantages of the invention will become apparent as the following

description of a present preferred embodiment thereof proceeds.

In the accompanying drawing I have shown a present preferred embodiment of the invention, wherein

Fig. 1 is a vertical cross-sectional view through a door having a latch structure applied thereto;

Fig. 2 is an elevational view of the latch structure shown in Fig. 1 viewed at right angles to Fig. 1;

Fig. 3 is a horizontal cross-sectional view through the latch mechanism; and

Figs. 4, 5 and 6 are vertical cross-sectional views through the latch mechanism, showing the respective parts thereof in various operative positions.

The latch structure of the described embodiment of the invention is of the general type of that disclosed and claimed in the co-pending application of William E. Wread, Serial No. 472,094, filed July 31, 1930, for the reissue of Patent No. 1,720,636 for latch unit, which application is owned by applicant's assignee.

Referring more particularly to the drawing, there is shown in vertical cross-section in Fig. 1 a door 2 provided with a transverse bore 3. The door is also provided with a lateral bore (not shown) communicating with the transverse bore 3 and extending laterally to the free edge of the door. Mounted in the transverse bore 3 of the door 2 is a casing comprised of a generally cylindrical body member 4 having a head 5 provided integrally with a smaller outwardly extending cylindrical bearing portion 6. Connected with the opposite side of the casing body is a removable head 7 having integral therewith an outwardly extending cylindrical bearing portion 8 similar to the bearing portion 6.

The casing body 4 is provided in its cylindrical surface with a generally radially extending substantially cylindrical hole 9. Threadedly connected with the casing body substantially directly opposite the hole 9 is a guide pin 10. For attachment of the guide pin the casing body has a threaded hole through which the body of the pin is adapted

- to pass and into which an enlarged threaded head 11 of the pin is adapted to be screwed, the pin also having a further enlarged head flange 12 provided with a slot 13 for the reception of a screw driver. Thus the guide pin 10 is readily attachable and detachable with respect to the casing body from the outside of the casing, greatly facilitating assembly and disassembly of the latch unit.
- 5 When the pin is screwed tightly into the casing body, its head flange 12 abuts against a shoulder 12a provided on the casing to insure proper positioning of the pin, and the pin is held rigidly with its body projecting into the casing substantially directly opposite the hole 9.
- 10 Slidably mounted with respect to the casing body 4, extending within the hole 9 and guided by the pin 10, is a bolt carrier 14.
- 15 The bolt carrier is preferably formed hollow, its inner extremity slidably receiving the pin 10, whereby to positively position and guide the carrier within the casing and substantially directly opposite the hole 9, and its outer extremity being preferably threaded for the reception of a bolt 15 to the outer end of which is threaded a head 16. The effective length of the bolt may be adjusted by turning it with respect to the carrier 14.
- 20 The bolt carrier 14 has a smooth substantially cylindrical outer surface 17 from which intermediate the extremities of the carrier projects outwardly an annular flange 18. Biased between the back of the casing body 4 and the flange 18 and surrounding the pin 10, and hence normally tending to urge the bolt carrier outwardly through the opening 9, is a coil spring 19 of relatively light construction for a reason to be presently made clear.
- 25 Slidably mounted upon the outer surface 17 of the bolt carrier 14 forwardly of the flange 18 and guided for reciprocation in a direction substantially parallel to the axis of the bolt carrier and relatively to the bolt carrier 14 is a retracting member 20. Preferably the bolt carrier and the retracting member 20 are splined together so that although relative reciprocation between them is permitted, they cannot rotate relatively to one another.
- 30 The splined connection between such members is omitted in the drawing for the sake of clearness.
- 35 The retracting member 20 has upwardly and downwardly extending crosshead portions 21 for a purpose to be presently described. Biased between the retracting member 20 and the back of the casing body is a coil spring 22 which substantially surrounds the coil spring 19 and also the guide pin 10.
- 40 The coil spring 22 is relatively heavy with respect to the coil spring 19 and imparts a substantially greater pressure to the retractor 20 than the spring 19 imparts to the bolt carrier 14. The two springs are in effect nested one within the other and thus exert substantially

coaxial compressive forces. Consequently the possibility of any tendency toward tilting of the retractor with respect to the bolt carrier is minimized, undue friction between the working parts is practically eliminated, and any noise created by friction of the moving parts against one another is greatly reduced. Such a spring arrangement has decided advantages over constructions using a plurality of eccentric springs, as if one of such springs should become bent or broken there would be a tendency for relative tilting between the latch members.

Journalized in each of the bearing portions 6 and 8 of the casing is a spindle 23 with which is connected a bearing sleeve 24 adapted to lie within the corresponding bearing portion and having at its outer extremity an outwardly turned annular flange 25 adapted to bear against the outer extremity of the bearing portion. Connected with the inner end of each bearing sleeve 24 is a plate 26 adapted to lie against a slight annular inward projection 27 formed on the casing and serving as a bearing member so that each spindle with the bearing sleeve and plate carried thereby is adapted for free rotation with respect to the corresponding bearing portion of the casing. Each spindle is maintained against axial movement by the plate 26 and the flange 25, which are effective for substantially embracing the corresponding cylindrical bearing portion of the casing. The inner extremity of each spindle is outwardly flared against the corresponding plate 26, as shown at 28.

Connected with the inner face of each of the plates 26 is a retracting cam 29 the opposite extremities of which are normally adapted to bear against one side of the retractor 20 when the retractor is projected as shown in Figs. 2, 3, 4 and 6, the spring 22 cooperating with the cam 29 for maintaining the retractor in normal position within the casing. The spring 19 normally urges the bolt carrier 14 outwardly of the casing and maintains the flange or shoulder 18 in contact with the retracting member 20. Thus the outward positions of both the bolt carrier and the retractor are determined by the cam 29.

The removable head 7 of the casing is provided with a slot 30 through which passes a locking slide 31 having an upwardly turned outer extremity 32 into which is threaded an operating button 33. The locking slide 31 is slidably mounted in suitable grooves provided in the casing body 4 and is adapted to move transversely of the casing upon operation of the button 33. The slide has a downwardly directed inner extremity 34 which normally lies substantially above the center of the casing. The respective crosshead portions 21 of the retractor 20 are provided substantially centrally with slots 35, the one of such slots which happens to be up-

permost, depending on whether the latch mechanism is used in a right- or a left-hand door, being adapted to receive the downward extension 34 of the locking slide 31 so that when such extension is within such slot free reciprocation of the retracting member is permitted. However, when the operating button 33 is pulled somewhat outwardly with respect to the casing, the portion 34 of the locking slide moves out of line with the corresponding slot 35 of the crosshead and is positioned behind the crosshead whereby to deadlock the same against retraction. The position of the locking member behind the crosshead member is shown in Figs. 1 and 2.

The downwardly extending portion 34 of the locking slide is made of the proper width to also deadlock the retractor 20 in retracted position if desired. The retractor is shown in retracted position in Fig. 5, and when it is in such position the portion 34 of the locking slide (not shown in such figure) may be moved out of line with the slot 35, thus holding the crosshead in retracted position independently of the retracting lug 29. A deadlocking slide construction similar to that above described is described and claimed in the copending application of Harry E. Woernle, Serial No. 412,083, filed Dec. 6, 1929, which application is owned by applicant's assignee.

The head 7 is maintained in place on the casing body 4 by bolts 36 which extend through the casing and engage the head 5 at the opposite side thereof. The position of the head 7 relatively to the casing may be reversed when it is desired to use the latch mechanism in a door of opposite hand, whereby to provide for the locking slide 31 to be disposed upwardly regardless of the hand of the door. The casing as a whole is adapted to be adjustably positioned within the bore 3 of the door 2 by means of positioning plates 37 disposed at opposite sides of the door and engaging the door at the edges of the bore 3. Bolts 38 pass through the respective plates 37 and through the casing and enable the plates to be tightened against the door. The casing may thereby be positioned as desired in the direction of the plane of the door. After such positioning in the direction of the plane of the door, the casing can be adjusted transversely of the door by sliding movement upon the respective bolts 38. This feature is described and claimed in the copending application of Harry E. Woernle, Serial No. 399,528, filed October 14, 1929, which application is owned by applicant's assignee.

Each of the bearing portions 6 and 8 of the casing is externally threaded and a positioning collar 39 is adapted to be screwed thereon. Cooperating with each positioning collar is a face plate or rosette 40 adapted to be pressed against the door when the collar

is tightened up on the casing. By relative adjustment of the respective collars the position of the casing transversely of the door may be adjusted as desired. The face plate at the inner side of the door is provided with an opening 41 through which the button 33 for the locking slide 31 is adapted to be operated. Threaded to each of the spindles 23 is a knob 42.

In operation, when the portion 34 of the locking slide 31 is in line with the slot 35 in the upper crosshead portion 21, turning of either knob 42 in either direction will cause rotation of the plate 26 and consequently of the cam 29, thereby withdrawing the retractor 20 and carrying with it the bolt carrier 14 and the bolt itself, as shown in Fig. 5. The turning of the knob effects the retraction of the bolt against the combined action of the springs 19 and 22, such springs imparting a substantial resistance to the knob, as is particularly desirable with doors and units of relatively heavy construction. Release of the knob allows the carrier and retractor to be urged outwardly by the springs 19 and 22, thus projecting the bolt.

When a door is pushed shut without turning either knob, the beveled face 43 of the bolt head 16 will engage the striker plate, thus camming the bolt and bolt carrier inwardly of the casing against the action of the spring 19, but without moving the retractor 20, as shown in Fig. 6. This is desirable because as little resistance as possible should be offered to the inward movement of the bolt when the door is closed in such manner. A differential resilient action is thus imparted to the bolt and carrier so that the desired amount of pressure is imparted to each of such devices at all times.

The locking slide 31 is effective in the manner heretofore explained for locking the retractor 20, but has no effect on the bolt itself. This is desirable because one may wish on leaving a room to first open the door and then set the locking slide to locked position and then push the door shut from the outside. The door will shut and cannot be opened by turning the outside knob. This would not be possible with a construction in which the locking slide deadlocks the bolt itself. Furthermore, if a door is substantially closed the locking slide may be brought into locking position even though due to some irregularity in the door frame the bolt may not be projected into the hole provided in the frame to its full extent. In such cases when a locking slide for the bolt itself is used it is necessary that the bolt be fully projected before the locking slide can be brought into locking position. When the retractor and bolt are in retracted position the locking slide will, however, be effective for maintaining the bolt itself retracted due to the fact that when the retractor is withdrawn into the casing it car-

ries the bolt with it and the bolt cannot be projected until the retractor is released.

Assembly and disassembly of the latch structure is rendered very easy by reason of the threaded connection between the guide pin 10 and the casing. After the head 8 has been removed and the guide pin unscrewed and withdrawn outwardly, the springs 19 and 22 are free to be removed from the end of the carrier, and after the bolt 15 has been unscrewed the carrier and retractor may be withdrawn from the casing.

The bolt head 16 will under usual circumstances be guided in a guide member positioned in the lateral bore at the edge of the door so that rotation of it is positively prevented and the desired adjustment of the latch may be maintained. The effective length of the bolt may be adjusted without varying the spring tension thereon.

While I have shown and described a present preferred embodiment of the invention, it is to be distinctly understood that the same is not limited thereto, but may be otherwise variously embodied within the scope of the following claims.

I claim:

1. Latch mechanism, comprising a casing, a bolt member reciprocable therein, a sleeve-like retractor for the bolt member reciprocable in the casing, the bolt member and retractor being concentrically mounted and being relatively reciprocable, and separate means within the casing for separately urging the bolt member and retractor outwardly with respect thereto.

2. Latch mechanism, comprising a casing, a bolt member reciprocable therein, a retractor for the bolt member reciprocable in the casing, the bolt member and retractor being relatively reciprocable, and separate means, both bearing against the rear wall of the casing, for separately urging the bolt member and retractor outwardly with respect thereto.

3. Latch mechanism, comprising a casing, a bolt member reciprocable therein, a retractor for the bolt member reciprocable in the casing, the bolt member and retractor being relatively reciprocable, and separate coil springs, one inside the other and both bearing against the casing, for separately urging the bolt member and retractor outwardly with respect to the casing.

4. Latch mechanism, comprising a casing, a bolt member reciprocable therein, a retractor for the bolt member reciprocable in the casing, the bolt member and retractor being relatively reciprocable, and separate concentric coil springs, one entering the other, one biased against the bolt member and the other against the retractor.

5. Latch mechanism, comprising a casing, a bolt member reciprocable therein and adjustable as to length, a retractor for the bolt

member reciprocable in the casing, the bolt member and retractor being relatively reciprocable, and separate means for separately urging the bolt member and retractor outwardly with respect to the casing and biased, respectively, between a rear surface of the bolt member and retractor and the rear casing wall, the length of the bolt member being adapted to be adjusted without varying the effect of the said means cooperating therewith.

6. Latch mechanism, comprising a casing, a bolt member reciprocable therein and adjustable as to length, a retractor for the bolt member reciprocable in the casing, the bolt member and retractor being relatively reciprocable, and separate means for separately urging the bolt member and the retractor outwardly with respect to the casing, such means cooperating with the bolt member being effective against the rear portion thereof and also bearing against the rear casing wall so that the effect of such means is not varied by varying the length of the bolt member.

7. Latch mechanism, comprising a casing, a bolt member reciprocable therein, a retractor for the bolt member reciprocable in the casing, the retractor being slidably mounted about the bolt member means for urging the bolt member outwardly with respect to the casing, and a coil spring for separately urging the retractor outwardly with respect to the casing, such coil spring being substantially coaxial with respect to the bolt member.

8. Latch mechanism, comprising a casing, a stationary guide pin mounted therein, a bolt member reciprocably mounted in the casing in guiding relationship to said guide pin, a retractor for the bolt member reciprocably carried about and guided by the bolt member and means for operating the retractor to retract the bolt member.

9. Latch mechanism, comprising a casing, a bolt member reciprocably mounted in the casing, a guide pin entering the bolt member, a retracting sleeve for the bolt member slidably thereon relatively thereto and carried and maintained in position thereby, and means for operating the retracting sleeve to retract the bolt member.

10. Latch mechanism, comprising a casing, bolt mechanism adapted for reciprocation with respect thereto, and guide means for the bolt mechanism, such guide means being connected with and extending within the casing, being supported thereby independently of the bolt mechanism and being readily disconnectable therefrom by manipulation from the outside of the casing.

11. Latch mechanism, comprising a casing, bolt mechanism adapted for reciprocation with respect thereto, and a guide member for the bolt mechanism, such guide member being adapted to extend within the casing, being threadedly connected therewith and be-

- ing adapted to be connected and disconnected therewith by manipulation from the outside of the casing.
12. Latch mechanism, comprising a casing, 5 bolt mechanism adapted for reciprocation with respect thereto, and a guide member for the bolt mechanism, such guide member being adapted to extend within the casing and being screw-threaded to and thereby directly supported from the casing so as to be readily disconnectable therefrom.
13. Latch mechanism, comprising a casing, a guide pin adapted to extend substantially rigidly within the casing and having a 15 threaded head threaded directly into the casing wall, and bolt mechanism slidably mounted on such pin.
14. Latch mechanism, comprising a casing, a guide pin mounted on the casing and adapted to extend into the same through an opening, and bolt mechanism slidably guided by such pin, such pin being readily detachable from the casing and removable outwardly therefrom through such opening to assist in 25 assembling and disassembling of the latch mechanism.
15. Latch mechanism, comprising a casing, a guide member projecting inwardly thereof, a bolt member slidably mounted about the 30 guide member, a retractor for the bolt member mounted in the casing and reciprocable with respect to the bolt member, and separate springs in the casing biased against the bolt member and retractor respectively.
- 35 16. Latch mechanism, comprising a casing, a guide member projecting inwardly thereof, a separate relatively slidable bolt member and retractor therefor guided by the guide member, and separate coil springs disposed about the guide member and biased against the bolt member and retractor respectively.
- 40 17. Latch mechanism, comprising a casing, a separate relatively slidable bolt member and retractor therefor guided in the casing, 45 a coil spring biased against the retractor, and a coil spring of less effect than the first mentioned coil spring disposed inside the first mentioned coil spring and biased against the bolt member.
- 50 18. Latch mechanism, comprising a casing, a guide pin screw threaded to the casing for ready disconnection therefrom, and a substantially coaxial bolt member and retractor therefor relatively reciprocable in the casing 55 and guided by said guide pin.
- 55 19. Latch mechanism, comprising a casing, a bolt member reciprocably mounted therein, a retractor for the bolt member slidably mounted on and held in place by the bolt member, means for operating the retractor, and means for deadlocking the retractor while still permitting slidable movement of the bolt member therein.
- 60 20. Latch mechanism, comprising a casing, a bolt member reciprocably mounted there-
- in, a retractor for the bolt member reciprocable with respect thereto and guided and held in place thereby, the bolt member and retractor being separately biased, means for operating the retractor, and means for deadlocking the retractor while still permitting slidable movement of the bolt member.
- 65 21. Latch mechanism, comprising a casing provided with an opening, a guide adapted to be inserted into and withdrawn from said casing through said opening and detachably fastened to the casing adjacent said opening, and a substantially coaxial bolt member and retractor therefor relatively reciprocable in the casing and guided by said guide.
- 70 22. Latch mechanism, comprising a casing provided with an opening, a guide adapted to be inserted into and withdrawn from said casing through said opening and detachably threaded to the casing and normally contained entirely within the confines thereof, and a bolt member reciprocable in the casing and adapted to be guided by said guide.
- 75 23. Latch mechanism, comprising a casing, a bolt member reciprocable therein, a generally sleeve-like retractor for the bolt member, said retractor being disposed about the bolt member and being mounted for slidable movement in the casing, and separate means for urging the bolt member and retractor outwardly of the casing.
- 80 In testimony whereof I have hereunto set my hand.
